UNITED STATES PATENT OFFICE.

VICTOR W. PAGÉ, OF NEW YORK, N. Y.

DESIGN FOR A MOTOR-VEHICLE RADIATOR.

57,784.

Specification for Design.

Patented May 3, 1921.

Application filed February 16, 1921. Serial No. 445,564. Term of patent 14 years.

To all whom it may concern:

Be it known that I, VICTOR W. PAGÉ, a citizen of the United States, and a resident of the city of New York, Kew Gardens, borough of Queens, in the county of Queens and State of New York, have invented a new, original, and ornamental Design for Motor-Vehicle Radiators, of which the following is a specification.

Reference is to be had to the accompanying drawing forming part thereof.

Figure 1 is a front elevation of a motor vehicle radiator showing my new design, and

Fig. 2 is a side elevation thereof.

I claim:

The ornamental design for a motor vehicle radiator as shown.

VICTOR W. PAGÉ.
